F. E. BEST

KEY

Original Filed May 23, 1923

FIG 1

FIG 2

Frank Ellis Best.
INVENTOR

UNITED STATES PATENT OFFICE.

FRANK ELLISON BEST, OF SEATTLE, WASHINGTON, ASSIGNOR TO FRANK E. BEST, INC.,
OF SEATTLE, WASHINGTON, A CORPORATION OF WASHINGTON.

KEY.

Application filed May 23, 1923, Serial No. 640,946. Renewed January 9, 1928.

My invention relates to improvements in keys for pin tumbler locks and the object of my improvement is to provide a key having stop means on its outer end by which 5 the position of the key in a lock is determined thereby making it possible to use the same key in locks having a different number of tumbler pins.

In my system of pin tumbler locks I find 10 it of advantage in many instances to construct or set up a plurality of different locks in such a manner as to render them capable of being operated by a single key. In carrying out this system it often happens that 15 it is desirable to use the same key in locks having a different number of tumbler pins so that in the locks having less than the maximum number of tumbler pins only a number of notches on the outer end of the key 20 corresponding to the number of tumblers in the lock will be used. This makes it desirable to provide means for accurately positioning the key relative to the tumbler pins regardless of the number of such tumbler 25 pins. All prior pin tumbler lock keys with which I am familiar have positioning devices located on the inner end of the key adjacent the finger piece. These positioning devices are designed to engage with the 30 outer ends of the respective locks to position the keys relative to the tumblers when the keys are inserted entirely into the locks and obviously would not be operative in case the key could not be inserted entirely into the 35 lock.

Providing the stop on the outer end of the key and providing suitable means in all locks with which said stop may engage makes it possible to use the same key successfully 40 in locks having less than the maximum number of tumblers which the key is capable of operating.

The stop on the end of the key is also used in positioning the key in a key cutting

machine in which the notches or serrations 45 in the edge of the key are formed. In the drawings Fig. 1 is a view in elevation of a key constructed in accordance with my invention.

Fig. 2 is a sectional view showing the key 50 in an operative position in a lock.

Referring to the drawings, throughout which like reference numerals designate like parts I have shown a pin tumbler lock key 3 of well known form that is provided on its 55 forward end with a notch 4 forming a shoulder 5 that is arranged to engage with a stop 6 formed in a pin tumbler lock 7, said stop means serving to properly align the notches or serrations, 8, in the edge of the key relative to the pin tumblers 9 in the lock.

The key 3 is capable of operating a lock with more tumblers than are provided in the lock 7 in which said key is shown in Fig. 2 to be inserted but it is obvious that the 65 stop means on the forward end of said key will operate in exactly the same manner regardless of the number of tumblers in the lock.

The shoulder 5 is also used for accurately 70 positioning the key in a key cutting machine in which the notches on the front edge of the key are formed.

The foregoing description and accompanying drawings clearly illustrate what I 75 now consider to be a preferred embodiment of my invention but it will be understood that changes in the same may be resorted to within the scope of the following claim.

I claim:

The combination with a pin tumbler lock having a separable key stop at its inner end, of a key having its rear edge notched at the forward end forming a shoulder arranged to engage with said stop for positioning said 85 key in said lock.

FRANK ELLISON BEST.
